UNITED STATES PATENT OFFICE

EDMUND L. DES JARDINS, OF CHICAGO, ILLINOIS

DISPLAY RACK

Application filed August 26, 1927. Serial No. 215,561.

This invention relates to a display rack which is adapted for displaying articles in a store window or which may be used as an easel or for other purposes.

5 The invention concerns itself with such a display rack which can be readily put together or taken apart, and which can be readily constructed of cardboard or the like.

The invention concerns itself further with 10 means for supporting articles at a low elevation for balancing the display rack and which extends through the display rack and forms rear props for the same.

The invention comprises the novel structure and combination of parts hereinafter described and more particularly pointed out and defined in the appended claims.

In the accompanying drawings, which illustrate a preferred embodiment of this invention and in which similar reference numerals refer to similar features in the different views:

Figure 1 is a front elevational view of my novel display rack.

25 Figure 2 is a side elevation thereof.

Figure 3 is a front elevational view of one of the rack elements.

30 Figure 4 is a side elevational view of the rack element shown in Figure 3, illustrating its assembly with a stanchion member such as a cardboard cover.

Figure 4^a is a side elevational view of a modified form of rack element adapted to carry a box cover in a position to display the 35 outer face thereof.

Figure 5 is an enlarged sectional view taken upon the line V—V of Figure 1 looking in the direction of the arrow.

Figure 6 is a sectional view taken upon the 40 line VI—VI of Figure 5.

Figure 7 is an enlarged sectional view taken upon the line VII—VII of Figure 2.

Figure 8 illustrates a stamped blank of 45 cardboard or the like from which certain rack elements may be formed.

Referring to the drawings, it will be noted that the display rack consists of a stanchion member 1 which may be formed of a flat piece of cardboard or the like. The base of the 50 stanchion member 1 extends horizontally in

order that it may rest upon a horizontal surface. The upper portion of the stanchion member may be of any desired configuration. In the present instance, it is shown as of a circular contour.

Upon one side of the stanchion member are 55 a pair of downwardly diverging slits 2 for receiving the diverging arms 3 of a rack element 4. It will be noted that the arms 3 extend intermediate the upper and lower elements of the rack element 4, as shown in Figure 5. The lower portions of the arm 3 are separated from the body portion of the rack element by clefts 5 which have straight walls 6 that contact with the stanchion member 7 and curved walls 7 that allow a rotational movement of the rack element. The cleft 5 terminates in a restricted slot at its upper edge of a size that would readily admit the thickness of the stanchion member 1. Between the upper ends of the arms 3 and the body portion of the rack element 4 are slots or notches 8 which are of a sufficient size to readily receive the stanchion member 1. Above the arms 3, the body portion has a spire 75 4^a having a frontal sloping surface 9 against which the stanchion member 1 may rest. It will be noted that the diverging arms 3 constitute the forward portions of the wings of a folded piece of cardboard or the like. The 80 aforementioned arms 3 are provided with downwardly sloping edges 10 which terminate in supporting shoulders 11 whereby it becomes possible to support an article such as a frame 12 or the like upon the rack element, as shown in Figure 1. In assembling the afore-described rack element with the stanchion member 1, the ends of the diverging arms are inserted through the diverging slots 2 in the stanchion member and the rear part of 85 the rack element is rotated downwardly until the cleft 5 aligns with the slots 2. The rack elements are then pushed forwardly until the slots engage the upper shoulders 3^a of the arms at which point a slight rotational movement will bring the rack element to the position shown in Figures 2 and 5, the rack element dropping down a short distance below the stanchion member as shown in Figure 5 due to the clefts 5. However, when the as-

sembled parts are positioned upon a horizontal surface, the rack element will be elevated to engage the slots 8 with the stanchion element for interlocking engagement therewith. It will be noted that in assembled 5 relationship, the rack element extends rearwardly of the stanchion member 1 and forms a prop therefor. The stanchion member rests against the straight surface 9 of the spire 10 4^a and the base of the spire 4^b lies in the same horizontal plane as the lower edge of the stanchion member 1 and supports the same. It will also be noted that the shoulders 11 on the diverging arm 3 are located relatively 15 low so that any articles that might be supported on the rack element will tend to stabilize the display rack.

Adjacent the rack element 4, there is shown a second rack element 13 which also consists 20 of a pair of diverging arms 14 just as in the first form. The rack element 13 is similar to the rack element 4 with regard to assembly and the manner of supporting the stanchion 1. It differs, however, in certain respects 25 which will now be described. The arms 14 of this rack 13, which may be termed a supplementary rack, have provision for a horizontal platform or table 15. The table 15 has a rear downwardly extending flap 16 that 30 enters the slot that receives the stanchion member 1. At the forward end of the table 15 are undercut or notched lugs 17, the forward edge of the table 15 fitting in the notches of said lugs as shown in Figures 1 and 2. 35 The arms 14 are also provided with downwardly sloping faces 18 terminating in supporting shoulders 11 whereby articles may also be supported in a manner similar to the rack element 4. The platform may be used 40 to support or display an article such as illustrated by the reference numeral 18.

Upon the upper portion of the stanchion element 1, there is shown a third rack element which consists of a cardboard device 19 45 or the like which is folded along the edge 20 and is so formed as to provide a pair of downwardly extending notched arms 21 having suitable tongues 22 at their lower ends for extending through suitable slots in the stanchion member 1. The notches are adapted 55 for holding paint brushes or pencils or the like as indicated by the reference numeral 27.

It will be noted that the upper ends of the arm 21 extend through suitable slots in the 55 stanchion member 1 and suitable notches or slots are provided between the arms and the rear portion 19 for receiving the stanchion member 1. Likewise, the tongues 22 are separate from the arms 21 by suitable notches 60 or slots for receiving the stanchion member whereby the third rack element may be securely interlocked with the stanchion member 1.

In Figure 3 is illustrated a rack element 4^c 65 somewhat similar to the first described rack

element 4. It has the same spire 4^a, the diverging arms 3 terminating in the shoulders 11. It merely differs from the rack element in that it is smaller and in that the lower edges of the arms 3 are cut out to provide a cleft 23 and a step portion 24. 70

In Figure 4, the rack element 4^c has been shown assembled with a cardboard box 25. It might be mentioned that the rack element 4^c is assembled in the same manner as the rack element 4 and in its assembled relation, the shoulder 26 formed between the cleft portion 23 and the step portion 24 fits in the corners of the box with one side of the box extending along the surface of the step portion 24. It will be noted that the box 25 also constitutes a stanchion member through which the rack member 4^c extends and which rack member supports the box by means of the spire 4^a and the lower rear surface 4^b, as in the first form. It will be appreciated that a box or cover containing handkerchiefs, ties, or similar articles may be readily displayed by simply inserting a rack member through either the bottom of the box or the lid, and a shallow box effect may thus be secured. 80

In some instances, where the box cover is highly decorated, it may be desirable to display the decorations as a background and it will be obvious that this may be accomplished by a modified form of rack element 27 having a spire 4^a, sloping edges 10 and supporting shoulders 11 similar to those illustrated in Figure 4. Each wing or arm 28 of the rack element is provided with a rectangular recess or notch 29 forming a squared shoulder 30 adapted to seat in a corner of a box cover 31 having a pair of slots 32 therein for receiving the wings or arms 28 of the rack element projected therethrough. In this manner the decorated outer face of the box cover may be conveniently displayed. 95

In Figure 8, there is shown on a smaller scale a blank 26 which is stamped or cut in proper form so that when the same is folded along its vertical center line, it will form the rack element 4 in its assembled relation. 110

From the foregoing, it will be appreciated that a very simple knock-down display rack has been provided which may be readily constructed of cardboard or the like in a very simple and cheap manner, and which may be used for displaying merchandise in a store window, on counters or other suitable places so that the merchandise may be conveniently seen and readily examined if desired. 115

I am aware that many changes may be made, and numerous details of construction may be varied through a wide range without departing from the principles of this invention, and I therefore do not purpose limiting the patent granted hereon, otherwise than necessitated by the prior art. 125

I claim as my invention:

1. In a display rack, a stanchion member 130

having slots and rack members having arms insertable through said slots by sliding and rotatable movement and slidably interlockable therewith.

- 5 2. In a display rack, a stanchion member having spaced slits, an article holding member having diverging parts, each having a shoulder and a cleft in alinement with said shoulder, said diverging parts extending through said slits and said shoulders and clefts being in alinement with said stanchion member.
- 10
- 15

In testimony whereof I have hereunto subscribed my name at Chicago, Cook County, Illinois.

EDMUND L. DES JARDINS.
